UNITED STATES PATENT OFFICE

2,342,404

HANDLE

Gerald V. Jakeway, Grand Rapids, Mich., assignor to Keeler Brass Company, Grand Rapids, Mich., a corporation of Michigan

Application June 12, 1941, Serial No. 397,676

14 Claims. (Cl. 292—347)

This invention relates to improvements in handle.

The main objects of this invention are:

First, to provide an improved handle or the like for automobile doors, remote controls, drawer pulls, and the like which may be produced in highly ornamental designs to match the desired finishes or plans of the structure to which it is applied.

Second, to provide a structure having these advantages which is simple and economical in its parts and in the assembly thereof and very strong and durable.

Third, to provide an improved method of manufacturing handles, remote controls, and the like which may be practiced for rapid production and with great economy.

Objects relating to details and economies of the invention will appear from the description to follow. The invention is defined in the claims.

Preferred embodiments of the invention are illustrated in the accompanying drawing, in which:

Fig. 1 is a side elevation partially broken away and in longitudinal section of a door handle embodying my invention.

Fig. 2 is an enlarged transverse section on line 2—2 of Fig. 1.

Fig. 3 is an enlarged transverse section on line 3—3 of Fig. 1.

Fig. 4 is a fragmentary view illustrating steps of the method employed in assembling and fabricating of articles embodying my invention, the parts being shown in full lines in their preformed shape and in assembled relation prior to the heat forming step and in completely assembled relation by dotted lines.

Fig. 5 is a cross sectional view similar to that of Fig. 3 of a modified form or embodiment of my invention.

In the embodiment of my invention illustrated in the accompanying drawing, 1 designates generally a handle such as is commonly employed for operating automobile doors, remote controls, and the like, the spindle or chill being indicated at 2. I have not attempted to illustrate other types of handles and remote controls for which my invention is well adapted.

In the embodiment illustrated, the handle comprises an elongated metal core 3 of rectangular section and suitable length. The spindle socket 4 is attached to this core, the details of attachment not being illustrated.

I provide an inner casing member 5 and an outer casing member 6, the casing 5 having an

internal channel 7 receiving and fitting the inner portion of the core, the outer member having an internal channel 8 receiving and fitting the outer portion of the core.

Figs. 2 and 3 are transverse sections of different parts of the handle and their difference in shape and transverse dimensions of the parts being due to the shape of the particular handle.

The inner casing member 5 is provided with 10 rearwardly projecting longitudinal ribs 9 adjacent the sides thereof, providing longitudinal grooves 10. The outer casing member is of such channel section that its sides 11 embrace the sides 12 of the inner member.

The edge portions 13 of the outer casing member are folded around the ribs 9 and into the grooves 10 in edge abutting relation to the bottoms of the grooves, thus clampingly retaining the casing members upon the core member.

In the preferred embodiment, both casing members are formed of thermoplastic material and are premolded, the sides 11 being in its premolded condition as shown in Fig. 4—that is, they are straight.

In assembling, the parts are arranged in nested relation, as shown in Fig. 4, and placed in the die member 14 and it will be observed that the sides of the outer casing member project substantially beyond the ribs 9 of the inner casing

30 member. The forming die 15 is provided with suitable heating means indicated at 16 and the die members are gradually closed as the edge portions of the sides of the premolded member 6 become heated. Preliminary heating and plasticizing might be resorted to—that is, heating before placing in the mold but that involves some difficulties in handling. I have illustrated electric heating means but gas or steam or other heating means might be employed. Where the

40 die is heated, its closing is suitably timed with the heating of the portions to be formed.

It will be noted that the die has curved recesses 17 which contact the heated edges of the outer casing member and as the die is closed 45 they are curled inwardly around the ribs 9 and into the grooves 10.

In this preferred embodiment, the edges of the outer casing member are brought into abutting supporting and retaining relation to the bottoms 50 of the grooves 10. If desired, some fusing action may result from the heating of these abutting portions or a solvent may be applied to effect a fused autogenous connection between these coengaging parts. However, the structure is very desirable without that feature.

The edges of the outer casing member are entirely concealed so that a unitary appearance results and in fact the completed structure is a unitary structure, with the outer casing member suitably conformed to the desired design or ornamentation and the inner casing member has a longitudinal rounded center portion 18 convenient for grasping.

This assembling operation may be quite rapidly performed. The resulting structure is strong and rigid and attractive in appearance. A great variety of colors and designs are possible.

In the modification shown in Fig. 5, the inner casing member 19 is formed of metal, otherwise the parts are very similar to those described.

Embodiments of the invention which incorporate the principles of the invention in a highly desirable manner have been illustrated and described. It should be understood that the foregoing terminology is used descriptively rather than in a limiting sense, and with full intention to include equivalents of the features shown and described, within the scope of the following claims.

Having thus described my invention, what I claim as new and desire to secure by Letters Patent, is:

1. In a hardware article, the combination of a core member of rectangular section, an inner casing member formed of thermoplastic material receiving the inner portion of said core member and provided with spaced longitudinal outwardly facing grooves and with a central projecting longitudinal portion between said grooves, and an outer casing member formed of thermoplastic material having an internal longitudinal channel receiving the outer portion of said core member and having side portions embracing the sides of said inner casing member, the sides of said outer casing member being extended around portions of said inner casing member with its inturned edges within the said grooves thereof and lying at the sides of said projecting longitudinal portion.

2. In a hardware article, the combination of a core member of rectangular section, an inner casing member receiving the inner portion of said core member and provided with spaced longitudinal outwardly facing grooves, and an outer casing member formed of thermoplastic material having an internal longitudinal channel receiving the outer portion of said core member and having side portions embracing the sides of said inner casing member, the sides of said outer casing member being extended around portions of said inner casing member with its inturned edges within the said grooves thereof.

3. In a hardware article, the combination of a core member, an inner casing member formed of thermoplastic material receiving the inner portion of said core member, and an outer casing member formed of thermoplastic material having an internal longitudinal channel receiving the outer portion of said core member and having side portions embracing the sides of said inner casing member, the sides of said outer casing member being extended around portions of said inner casing member with inturned edges abutting portions thereof.

4. In a hardware article, the combination of a core member, an inner casing member receiving the inner portion of said core member, and an outer casing member formed of thermoplastic material having an internal longitudinal channel

receiving the outer portion of said core member and having side portions embracing the sides of said inner casing member, the sides of said outer casing member being extended around portions of said inner casing member.

5. In a hardware article, the combination of a core member, an inner casing member formed of thermoplastic material channeled to receive the inner portion of said core member and having side portions provided with rearwardly facing longitudinal grooves, and an outer casing member formed of thermoplastic material of channel section embracing the outer portion of said core member and the side portions of said inner casing member, the sides of said outer casing member being extended around said inner casing member with its edges within said grooves of said inner casing member.

6. In a hardware article, the combination of a core member, an inner casing member channeled to receive the inner portion of said core member provided with rearwardly facing spaced longitudinal grooves, and an outer casing member formed of thermoplastic material of channel section embracing the outer portion of said core member and the side portions of said inner casing member, the sides of said outer casing member being extended around said inner casing member with its edges within said grooves of said inner casing member.

7. An ornamental hardware article comprising coacting opposed casing members of non-metallic thermoplastic ornamental material premolded in a generally channel section, and an operating element internally receivable in said members and operatively positioning the same, said members being disposed with the side extremities of one lying internally of those of the other, the side extremities of the outer member being curled around approximately 180° and engaged with the inner member internally of the side confines of the article.

8. An ornamental hardware article comprising coacting opposed ornamental thermoplastic casing members, at least one of which is of a generally channel section, said members being disposed with the side extremities of one internally of those of the other and the side extremities of the outermost member being curled around approximately 180° and engaged with the innermost member at points internally of the side confines of the article.

9. In a hardware article, the combination of an inner casing member formed of thermoplastic material and having a rearwardly extending rib adjacent the side thereof defining an external groove, and an outer casing member formed of thermoplastic material receiving the side portions of said inner casing member, said outer casing member being of channel section having its side extended around said inner casing member with its edge turned inwardly and forwardly and lying within said groove in abutting relation to said inner casing member.

10. In a hardware article, the combination of a core member, an inner casing member provided with external channels, and an outer casing member formed of thermoplastic material receiving the side portions of said inner casing member, said casing members being of channel section and being in embracing supported relation to said core member, the sides of the outer casing member being extended around said inner casing member with its inturned edges within said grooves.

11. In a hardware article, the combination of a core member, an inner casing member formed of thermoplastic material and having longitudinal external grooves, and an outer casing member formed of thermoplastic material, said casing members being of channel section and being in embracing supported relation to said core member, the sides of the outer casing member being extended around the edges of said inner casing member with its inturned edges disposed within the said grooves thereof.

12. In a hardware article, the combination of a core member, an inner casing member supportingly engaged with said core member and having rearwardly facing longitudinal rib-like portions, and an outer casing member of premolded thermoplastic material and of channel section supportingly engaging said core member and the sides of said inner member and having the edges thereof turned inwardly and forwardly around the said rib-like portions of said inner member.

13. In a hardware article, the combination of an inner rear casing member having rearwardly facing longitudinal rib-like portions, and an outer

front casing member of premolded thermoplastic material and of channel section supportingly engaging the sides of said inner member and having the edges thereof turned inwardly and forwardly around said rib-like portions into retaining engagement with said inner member.

14. In a hardware article, the combination of a core member of rectangular section, an inner casing member formed of thermoplastic material receiving the inner portion of said core member and provided with spaced longitudinal outwardly facing grooves and with a central projecting longitudinal portion between said grooves, and an outer casing member formed of thermoplastic material having an internal longitudinal channel receiving the outer portion of said core member and having side portions embracing the sides of said inner casing member, the sides of said outer casing member being extended around portions of said inner casing member with its inturned edges within the said grooves thereof and lying at the sides of said projecting longitudinal portion.

GERALD V. JAKEWAY.
